Patented Oct. 21, 1924.

Des. 65,801

UNITED STATES PATENT OFFICE.

CHARLES C. CROSSLEY, OF STRUTHERS, OHIO.

DESIGN FOR A MONUMENTAL VASE.

Application filed May 14, 1923. Serial No. 6,158. Term of patent 7 years.

To all whom it may concern:

Be it known that I, CHARLES C. CROSSLEY, a citizen of the United States, residing at Struthers, in the county of Mahoning and State of Ohio, have invented a new, original, and ornamental Design for a Monumental Vase, of which the following is a specification, reference being had to the accompanying drawing, forming part thereof.

The figure is a front elevation of a monumental vase showing my new design.

I claim:—

The ornamental design for a monumental vase as shown.

CHARLES C. CROSSLEY.

Witnesses:

J. M. REED,

T. R. GORDON.
